UNITED STATES PATENT OFFICE.

GEORGE HENRY WHEARY, OF RACINE, WISCONSIN.

WARDROBE-TRUNK.

1,243,366.

Specification of Letters Patent. Patented Oct. 16, 1917.

Application filed January 27, 1913. Serial No. 744,376.

To all whom it may concern:

Be it known that I, GEORGE HENRY WHEARY, a citizen of the United States, and resident of Racine, in the county of Racine and State of Wisconsin, have invented new and useful Improvements in Wardrobe-Trunks, of which the following is a description, reference being had to the accompanying drawings, which are a part of this specification.

10 This invention relates to improvements in wardrobe trunks of that type in which the trunk is adapted to stand on one end and is divided vertically, medially to form a main body section and a wardrobe section, 15 the wardrobe section being hinged to the body section and adapted to be swung horizontally to open position.

It is one of the objects of the present invention to provide a wardrobe trunk of the 20 before mentioned type in which the upper end portions of the body section and the wardrobe section are covered over and overlapped by an upper cover to form a water-proof closure and to strengthen the general 25 structure of the trunk.

A further object of the invention is to provide a wardrobe trunk having garment supporting means in which the hangers thereof may be moved out of the wardrobe 30 section to a position of convenient accessibility to permit the removal or replacement of garments from or in said section.

A further object of the invention is to provide a wardrobe trunk which is of simple 35 construction, is strong and durable and is well adapted to withstand the hard usage trunks are usually subjected to.

With the above and other objects in view, the invention consists of the improved 40 wardrobe trunk and its parts and combinations as set forth in the claim, and all equivalents thereof.

In the accompanying drawings in which the same reference characters indicate the 45 same parts in all of the views:

Figure 1 is a top view of the improved wardrobe trunk shown with the upper cover in open position, the wardrobe section also being indicated in open position by dotted 50 lines;

Fig. 2 is a vertical sectional view of the upper portion of the trunk, the upper cover being indicated in open position by dotted lines;

55 Fig. 3 is a top view in closed position, of the garment supporting tracks of the trunk,

the arms of the tracks also being indicated in partly open position by dotted lines;

Fig. 4 is a top view of a modified form of trunk and garment supporting tracks, 60 the upper cover being in open position and the wardrobe section being indicated in open position by dotted lines; and

Fig. 5 is a side edge view thereof with the upper cover shown in open position and 65 a portion of the wardrobe section broken away to show interior construction.

Referring to the drawings the numeral 8 indicates the trunk body generally which is divided centrally, vertically to form a 70 body section 9 and a wardrobe section 10 hinged thereto and arranged to swing horizontally to open position.

An upper or top cover 11 hinged to the body section of the trunk a short distance 75 below the upper edge thereof is arranged to extend and overlap the end portions of both sections and the end portions of said parts are recessed as indicated by the numeral 12 to receive the cover. This construction 80 securely locks the wardrobe section to the body section when the cover is in closed position and as the cover extends over the upper joint of the two parts rain or snow cannot enter when the trunk is exposed to the elements. 85

The cover is provided with a swelled portion 13 to prevent the trunk from being placed upside down and to indicate the top 90 of the trunk.

To provide a simple means for locking the two sections of the trunk and the upper cover together the upper cover is locked to the wardrobe section by an ordinary lock 95 14 and the wardrobe section is locked to the body section by two locks 15 which are unlocked by pulling on the rod 16 which is exposed to view when the upper cover is swung upwardly to open position. The rod is connected to the lock bolts 17 by chains 18. 100

The wardrobe section of the trunk is provided with hanger tracks 19 which support garment hangers 20 slidably mounted thereon. In this form the hanger tracks are of approximately the length of the depth of 105 the wardrobe section and are provided with hinged extension arms 21 which may be swung horizontally outwardly to position in alignment with the tracks when the wardrobe section is swung to open position so that the garment hangers may be slid out 110 of the said section and on the extensions.

The free ends of the extensions are locked together when in closed position by the coupling sleeve 22 which is slidably mounted on one of the extension arms and is adapted to 5 slide over the end of the other arm. The sleeve has a pin and slot connection 23 with the arm upon which it is mounted to permit its sliding engagement with the other arm and to prevent it from accidentally slipping 10 off the rod.

The upper cover is provided with a cushion lining 24 which serves to hold the garment hangers in position on the tracks when the cover is closed and is also provided with a 15 linked connection 25 to hold the cover in open position.

Another point of advantage possessed by this construction of trunk is that garments 20 may be removed from the wardrobe section or from the upper compartments of the body section without swinging the wardrobe section to open position. To permit the removal of apparel from the body section a removable top or cover 29 is provided for 25 the hat compartment 30 and the bottom of this compartment is also provided with a removable bottom portion 31 to permit access to the drawer 32 therebelow and also to combine the compartment and drawer in 30 one space to hold larger hats or other wearing apparel when desired.

In the modified form of trunk shown in Figs. 4 and 5 the inner upper wall of the compartment 26 of the wardrobe section of 35 the trunk terminates a short distance from the upper cover to provide space between the cover and the compartment wall to accommodate the fixed extensions 27 of the

hanger tracks 28. These extensions are formed integral with the tracks and project 40 out of the wardrobe section approximately the same distance as the extensions previously described and possess all of the advantages thereof in providing for the sliding outwardly of the garment hangers on 45 said extensions.

From the foregoing description it will be seen that the wardrobe trunk is well adapted for the purpose described.

What I claim as my invention is:

A wardrobe trunk, comprising a trunk body divided medially vertically to form a wardrobe section and a drawer section which are hinged together at one of their side portions, the lower ends of said sections being closed and the upper ends being open and provided exteriorly with recessed portions, garment hanger tracks mounted in one of the sections and having extensions which project out of the section 60 when the sections are in open position, and a cover hinged to the drawer section and covering and overlapping the open ends of both sections and entering the recessed portions thereof when said sections are in closed position, both sections being constructed to permit the removal of apparel therefrom when the two sections are in closed position and the cover is in open 65 position.

In testimony whereof, I affix my signature, in presence of two witnesses.

GEORGE HENRY WHEARY.
